ATTORNEY

Patented Nov. 10, 1925.

UNITED STATES PATENT OFFICE.

GEORGE WADE, OF NEWARK, NEW JERSEY.

HEATING MEANS.

Application filed May 25, 1925. Serial No. 32,597.

To all whom it may concern:

Be it known that I, GEORGE WADE, a citizen of the United States, and a resident of the city of Newark, county of Essex, and 5 State of New Jersey, have invented certain new and useful Improvements in Heating Means, of which the following is a specification sufficient to enable those skilled in the art to which the invention appertains to 10 utilize the same.

My improvements relate to what may be designated as a hydro-electric radiator for heating purposes in which an electric resistance coil is utilized to raise the temperature 15 of water contained in a suitable unit by which the heat is imparted to the adjacent atmosphere,—the invention consisting, in the specific structure and combination of parts described and claimed herein.

20 In the accompanying drawings I illustrate a practical embodiment of the essential features of my invention in connection with a radiator of the character designated.

Fig. 1, is a side elevation of the heat radi- 25 ator;

Fig. 2, is an end elevation thereof;

Fig. 3, is a sectional elevation taken upon the planes of the angular line indicated by 3—3, Fig. 2;

30 Fig. 4, is a full sized detail of the electrical heating unit, the resistance coil being shown in elevation, and heating chamber in central longitudinal section;

Fig. 5, is an elevation of the inner side of 35 the heating chamber cap shown in the preceding figures of the drawings;

Fig. 6, is a side elevation thereof;

Fig. 7, is a side elevation of the exterior 40 of the heating chamber as formed with hex-
agonal head;

Fig. 8, is an end elevation thereof; and

Fig. 9, is a sectional detail, similar to Fig. 4, showing a modification in the form of 45 closure cap for the heating chamber, adapt-
ed particularly for use in conjunction with hexagonal head shown in Figs. 7 and 8.

In said drawings R, represents the equiva- 50 lent of a sectional radiator of the steam or hot water type, assembled and sealed in a manner well known in the prior art, but in the present case closed in such manner as to retain a suitable quantity and level of water to act as the heat absorbing and distribut-

ing vehicle or medium. Thus, screw plugs 55 r, r, close the usual upper and lower end tops, and the upper portion of the radiator is provided with the customary pet cock r'. As heretofore, the conjunctive upper and lower portions of the radiator sections constitute respectively an upper horizontal longitudinal space or chamber r², and a corresponding lower space or chamber r³, the latter of relatively larger area. It is in this lower water space r³, that I position my heating chamber H, for the accommodation of the 60 electric heating coil E, which is mounted in a socket S, in a manner well known in the art, said heating unit E, S, being a commercial commodity and being utilized in this connection as a conveniently available component part of my new hydro-electric radiator, considered in a unitary sense.

The socket S, is connected upon occasion with a suitable electric circuit by means of the usual wire conduit s, and plug s', as indicated more particularly in Fig. 1, of the drawings.

The outer extremity or head of the heating chamber H, is peripherally screw threaded, as at h, for engagment with a female screw thread tapped for the purpose in the lower portion of the radiator in alignment with the aforesaid lower water space r³, into which the contracted portion of the chamber H, protrudes, as shown more particularly in Fig. 3, of the drawings.

The said outer end or head of the heating chamber H, is closed by a cap C, which also functions as a support for the socket S, of the heating coil E, as will be seen by reference more particularly to Figs. 4 and 9, of the drawings, and this cap may fit the head externally as provided for in the first six figures of the drawings, or internally as in Fig. 9, thereof. In either case the cap C, is 90 preferably formed with vent holes c, c, which admit of a neutralization of air pressure within the heating chamber and for a slight degree of air circulation sufficient to prevent overheating.

The absence of steam or hot water pipes and connections renders my hydro-electric radiator portable in character; and the sanitary advantages of heating with water as a 95 vehicle for heat dissemination are well known in the art.

What I claim as my invention and desire to secure by Letters Patent, is:—

In combination with a sealed radiator containing a liquid heat vehicle, a one piece heating chamber positioned therein and formed with a head protuberant therefrom, a cap fitting the said head of the heating chamber and constituting a seat for a re-

movable electric socket, said electric socket, an electric heating coil incorporated with 10 said electric socket and frictionally engaging said cap, and means for connecting said socket and heating element with an electric circuit, substantially in the manner and for the purpose set forth.

GEORGE WADE.
